(57) **CLAIM**

The ornamental design for a shrouded current transformer, as shown and described.

DESCRIPTION

FIG. 1 is a perspective view of a shrouded current transformer, showing my new design;

FIG. 2 is a front elevation view of FIG. 1, the rear elevation view being a mirror image thereof;

FIG. 3 is a top plan view of FIG. 1;

FIG. 4 is a right side elevation view of FIG. 1;

FIG. 5 is a left side elevation view of FIG. 1; and,

FIG. 6 is a bottom plan view of FIG. 1.

The broken lines in the drawing views are included for the purpose of illustrating unclaimed environment only, and forms no part of the claimed design.
